UNITED STATES PATENT OFFICE

WINFRED S. GRIFFITH, OF WORCESTER, MASSACHUSETTS, ASSIGNOR TO GRATON & KNIGHT COMPANY, OF WORCESTER, MASSACHUSETTS, A CORPORATION OF MASSACHUSETTS

LEATHER-SCRATCHING MACHINE

Application filed May 14, 1928. Serial No. 277,752.

This invention relates to a machine particularly designed for preparing the flesh side of a belt prior to a cementing or gluing operation. Before cementing together the 5 two parts of a double leather belt, it is essential that all fleshy parts of the leather be removed and that the inner surface of the belt be brushed or scratched to give it a uniform and slightly roughened surface.

10 These operations have been heretofore commonly performed by scraping and carding manually, and it is the general object of my invention to provide mechanical means by which equivalent operations may be effectively performed at a substantial saving of 15 time and material. My present invention relates specifically to a machine for scratching or raising the fleshy material from the flesh side of the belt so that it may be conveniently removed at a subsequent operation.

20 More particularly, I provide a roughened scratching cylinder rotating at relatively high speed and I provide especially designed means for pressing the flesh side of a leather 25 belt against the rotating cylinder with a substantially uniform pressure throughout its width, regardless of variations in the thickness of the leather.

25 My invention further relates to arrangements and combinations of parts which will be hereinafter described and more particularly pointed out in the appended claims.

A preferred form of the invention is shown 30 in the drawings in which

35 Fig. 1 is a plan view of my improved scratching machine;

Fig. 2 is an end view of certain parts, looking in the direction of the arrow 2 in Fig. 1;

40 Fig. 3 is a sectional end elevation, taken along the line 3—3 in Fig. 1, and

Fig. 4 is a detail side elevation, looking in the direction of the arrow 4 in Fig. 3.

45 Referring to the drawing, my improved scratching machine comprises a frame 10 (Fig. 3) having tables or supports 11 and 12 mounted thereon. A lower feed roll 13 is rotatable in fixed bearings in the frame 10 and is provided with a spiral gear 14 engaged 50 by a corresponding spiral gear 15 (Fig. 2) on a cross shaft 16, mounted in bearings at the

end of the frame 10. A worm gear 17 is secured to the cross shaft 16 and is engaged by a worm 18 on a roll shaft 19 rotatable in bearings 20 (Fig. 1) supported by the frame 10 and having a driving pulley 22 secured thereto and rotated by a belt 23 from any suitable source of power.

55 A scratching roll 24 (Fig. 3) is mounted on the shaft 19 and is provided with a roughened surface, which may preferably be formed by securing a covering of cardclothing 25 to the periphery thereof. The roll 13 is commonly of wood and is preferably provided with an outer surface 27 of leather, as shown in Fig. 3. With the driving connections shown, it will appear that the feed roll 13 will rotate at slow speed while the scratching roll 24 rotates at comparatively high speed.

60 A second feed roll 30 is mounted in bearing blocks 31 which are vertically adjustable in guide-ways 32 supported on the frame 10. The blocks 31 are held in their lowermost position by springs 33 and the downward limit of the roll may be adjusted by wing nuts 34 on studs 35 extending upward from the boxes 31. The roll 30 is preferably provided with a relatively thick and soft covering 37 of rubber which will yield to the inequalities 65 of the belt as it passes thereunder.

70 A series of presser fingers 40 are pivoted on a cross rod 41, supported in brackets 42. A cross bar 43 connects the brackets at opposite sides of the machine. Bolts 44 are secured to the brackets 42 and extend through plates 45 fixed to fixed portions of the feed roll bearing 75 frames.

75 Heavy coil springs 46 force the presser fingers 40 and their supporting structure to the right, as viewed in Fig. 3, and such movement is limited by wing nuts 47 on the bolts 44. By turning the nuts 47, the presser fingers may be positioned in desired relation to the scratching roll 24.

80 Each presser finger has a belt contacting element 48 inserted in its lower face, preferably formed from a small disc of hardened steel forced into an opening in the lower edge of the finger and positioned to engage the belt directly above the scratching roll 24. Each 85

finger 40 also has an upward extension 50, having an opening therein through which loosely extends a bolt or screw 51 threaded in the cross bar 43.

5 A coil spring 52 surrounds each screw 51 and provides yielding resistance to upward movement of each separate finger. The vertical position of the contact faces of the fingers and also the spring tension thereon 10 may be adjusted by turning the screws 51.

10 Having thus described my invention, the method of operation is as follows:

A belt B is fed into the machine over the table 11 and is engaged between the surfaces 15 of the feed rolls 13 and 30, by which it is slowly advanced to the brushing roll 24 and presser fingers 40. The card-clothing 25 rotates at very much greater speed than the travel of the belt but in the same direction, 20 and acts to tear up the soft fleshy material remaining on the under side of the belt. The fingers 40 are self-adjusting and apply substantially uniform pressure of the belt throughout its width, regardless of variations 25 in the thickness of the leather.

It is frequently desirable to run the belt through the scratching machine two or more times before skiving off the projecting fleshy material and this is readily accomplished by 30 looping the end of the belt over the machine and again inserting it between the feed rolls, the rolls being of such length that the belt may pass several times through the machine simultaneously if desired.

35 For guiding the belt over the table 11 to the feed rolls, I provide a plurality of guide-pins 60, which may be inserted in selected holes 61 spaced across the table 11. By inserting several such guide-pins, the belt may 40 be passed several times through the machine in succession and the different loops of the belt will be kept separate and will be prevented from interference with each other.

When the belt leaves the machine, the 45 fleshy material extends loosely from the flesh side of the belt and may thereafter be easily removed therefrom by a skiving or shaving operation.

Having thus described my invention and 50 the advantages thereof, I do not wish to be limited to the details herein disclosed, otherwise than as set forth in the claims, but what I claim is:—

1. A belt scratching machine comprising 55 feeding mechanism, a scratching cylinder provided with a great number of stiff outwardly projecting teeth of substantially uniform length, and means to press against said scratching cylinder at substantially uniform 60 pressure the flesh side of all portions of a belt fed through said machine, said pressure being substantially independent of minor variations in belt thickness.

2. A belt scratching machine comprising 65 feeding mechanism, a scratching cylinder

provided with a great number of stiff outwardly projecting teeth of substantially uniform length, and a plurality of independently operating pressure devices effective to press against said cylinder at substantially uniform pressure all portions of a belt fed through said machine, said pressure being substantially independent of minor variations in belt thickness. 70

3. A belt scratching machine comprising 75 feeding mechanism, a scratching cylinder provided with a great number of stiff outwardly projecting teeth of substantially uniform length, and a plurality of presser members each yieldingly and independently engaging a belt fed through said machine and effective to press all portions thereof against the scratching cylinder at substantially uniform pressure, said pressure being substantially independent of minor variations in 80 belt thickness. 85

4. A belt scratching machine comprising 90 feeding mechanism, a scratching cylinder provided with a great number of stiff outwardly projecting teeth of substantially uniform length, a plurality of presser fingers, and a separate spring for each finger effective to press each finger independently of the other fingers against a belt fed through said machine, said fingers being collectively effective to press all portions of said belt against said scratching cylinder at substantially uniform pressure. 95

5. A belt scratching machine comprising 100 feeding mechanism, a scratching cylinder provided with a great number of stiff outwardly projecting teeth of substantially uniform length, a plurality of presser fingers mounted on fixed pivots, and a separate spring for each finger effective to swing each finger on its pivot independently of the other fingers against a belt fed through said machine, said fingers being collectively effective to press all portions of said belt against said scratching cylinder at substantially uniform pressure. 105

6. In a belt scratching machine, a pair of 110 feed rolls, a scratching cylinder covered with card clothing and rotatable in the direction of belt travel, a support for the belt as it approaches the feed rolls, and means to guide the belt in a selected path of approach. 115

7. In a belt scratching machine, a pair of 120 feed rolls, a scratching cylinder covered with card clothing and rotatable in the direction of belt travel, a support for the belt as it approaches the feed rolls, and means to guide the belt in a selected path of approach, said means being adjustable axially of said feed rolls. 125

8. In a belt scratching machine, a pair of 130 feed rolls, a scratching cylinder covered with card clothing and rotatable in the direction of belt travel, a support for the belt as it approaches the feed rolls, and means to guide

the belt in a selected path of approach, said support having a plurality of holes spaced longitudinally of said rolls, and said means comprising a plurality of guide-pins mounted in selected holes in said support.

5 In testimony whereof I have hereunto affixed my signature.

WINFRED S. GRIFFITH.
